UNITED STATES PATENT OFFICE.

JOHN YOUNG, OF CHILLICOTHE, OHIO.

BALING-PRESS.

1,114,090.

Specification of Letters Patent.

Patented Oct. 20, 1914.

Application filed August 12, 1912. Serial No. 714,593.

To all whom it may concern:

Be it known that I, JOHN YOUNG, a citizen of the United States, residing at Chillicothe, in the county of Ross and State of 5 Ohio, have invented certain new and useful Improvements in Baling-Presses, of which the following is a specification.

My invention relates to baling presses and pertains particularly to baling presses of 10 the type comprising a receptacle and a reciprocating plunger working therein.

My invention may take various forms, but desirably comprises the structure shown in the accompanying drawings, in which similar characters of reference designate corresponding parts, and in which:

Figure 1 is a side elevation of my improved baling press in complete form, Fig. 2 is a plan view of my baling press showing portions 20 thereof removed for a clearer presentation of the base structure of the receptacle of the baling press and of the trackway desirably utilized, Fig. 3 is a side elevation partially broken away of my improved baling press and showing one of the sides of 25 the receptacle removed therefrom, Fig. 4 is a perspective of my improved type of receptacle showing one of the sides removed, Fig. 5 is a detail view of one of the sides of 30 my baling press receptacle shown in perspective, Fig. 6 is a detail of one of the roller lever elements preferably utilized by me in a manner to be described, and, Fig. 7 is a section taken on line 7—7 of Fig. 6.

In the preferred form of my invention, it embodies a reciprocating plunger 1, racks 2 and 3 upon which said plunger is mounted and which coöperate with pinions 4 and 5 upon a shaft 6 driven by gearing desirable 35 similar to the structure of gearing shown in my application, Serial Number 690,627. More specifically, this gearing structure comprises a hand wheel 7 slidably splined to slide upon one end of the shaft 6 and capable when in its outermost position of 40 directly driving the shaft 6 for the production of a high speed of travel of the reciprocating plunger in either direction of movement. The hand wheel 7 preferably carries 45 a cog 8 upon its inner extremity for coaction with a toothed socket in the side of a gear 9. This gear 9 is adapted to be driven by an intermeshing gear 10 carrying concentrically a worm wheel 11 under the control 50 of a worm 12 having a hand wheel 13 for op-

erating the same. It will be understood that the movement of the wheel 7 into intermeshing relation with the toothed socket in the wheel 9 and a subsequent rotation of the hand wheel 13 will serve to drive the shaft 60 6 and will enable the application of considerable power thereto. From this structure, it will be seen that I am enabled to rapidly reciprocate the plunger or am enabled to slowly and more powerfully reciprocate the said plunger.

In the drawings, my baling press is comprised of a base structure formed of transverse base angle irons 14 and 15 carrying double inclined trackways 17 and 18 which 70 may be formed of angle irons bent to proper shape and which are desirably supported by longitudinal channel irons 19 centrally located and firmly supporting the trackways 17 which are bent to conform at this point. 75 These trackways 17 are preferably provided with latches 20 and 21 disposed at points intermediate their lengths for a purpose to be hereinafter described.

Connected to the channel irons 19 and 80 rising centrally from either side of the base structure, are standards 22 and 23 and these standards are provided at their upper ends with bearings for the support of the shaft 6. It will be understood that these bearings 85 may vary as to form.

Coacting with the plunger of my improved baling press and with the base thereof is a receptacle designed to normally rest upon the base structure at a comparatively 90 central point thereof to relieve the receptacle of the strains caused by the downward pressure of the plunger and capable of movement laterally down either inclined track to be effected by a peculiar normally ineffective roller structure to be hereinafter 95 described. This receptacle of my baling press is preferably comprised of a shallow pan-like structure 24 having end flanges 25 and 26 and having vertical standards 27 supporting a rectangular framework 28 formed from a piece of metal of L-shaped cross section. The flanges 25 of the pan 24 preferably have slots 29 and bearings 30 for a purpose to be hereinafter described. This 100 pan structure 24 is further provided with a plurality of spaced transversely extending boards or supports 31 having cut-out portions 32 and opposing studs 33 preferably of rounded contour and desirably substan- 110

tially concentric to the said cut-out portions 32. Co-actively mounted upon the rectangular framework 28 through means of hinges 34 are end pieces 35 which normally 5 maintain a position substantially vertical and in substantial parallelism to the brace pieces 27 and which are preferably forced inwardly against adjacent boards 31 by eccentric elements on said braces 27 in the 10 form of shafts 36 in bearings 37 and having fingers 38 together with operating handles 39. The manner of operation of this structure is very simple, in that the movement of the levers 39 in one direction will serve 15 to force the fingers 38 into contact with the end pieces 35 and in turn to force the said end pieces 35 into contact with the end boards 31. These end pieces 35 are preferably provided with latch elements 40 pivoted 20 at 41 and having limiting pins 42 coacting with slots 43. Each of these end pieces is preferably provided with one of these latch elements on either side thereof and these latch elements coact with keepers 44 on the 25 side pieces 45. The side pieces 45 are preferably of a simple structure, being provided with plane inner surfaces and being provided on their outer surfaces with handle pieces 46, whose ends form the keepers 44. 30 The side pieces 45 are placed in position by placing their bases between the cut-out ends of the bars or boards 31 and the series of studs 83 and then causing the upper edge of the said side pieces 45 to move into contacting 35 relation to the depending legs of the rectangular iron 28. This position is maintained by the locking of the latches 40 over the said keepers 44 in the manner which will be apparent.

40 Disposed upon the flanges 25 of the base plate 24 and fulcrumed in the bearings 30 are roller levers 46^a having fulcrum pins 47 and rollers 48 journaled thereon by means of bolts 49, sleeves 50 and nuts 51. These 45 roller levers 46^a are preferably disposed two on each of the flanges 25 and at either end thereof and are joined in opposing pairs by means of longitudinal strips 52 which may be integrally formed with the levers 46^a. 50 Also, these roller levers are provided with lateral outward extensions 53 and these outward extensions 53 are designed to normally coöperate with latches 20 and 21 for maintaining the receptacle structure in a 55 comparatively central position as will be shown best in Figs. 1 and 2. It will also be apparent from reference to Fig. 2 that the driving shaft 6 is disposed slightly to one side of the center and this is for the purpose 60 of maintaining a substantially central alinement of the packing plunger.

In operation, my improved baling press being in the position shown in Fig. 1 and being empty, one of the connecting pieces 65 52 is grasped and the roller levers elevated

to release the members 53 from their latches and to raise the base of the receptacle from its normal position of support upon the supporting channel irons 19 by the leverage action of the rollers upon the tracks. While 70 in this position, the weight of the receptacle being transferred to the rollers, it is moved laterally until it passes a central point, when it will have a tendency to slide down the incline track into a position for filling, 75 it being, of course, understood that previous to this operation the packing plunger has been moved to a position where it will be out of the path of movement of the receptacle. The movement of the receptacle down 80 either inclined track is limited by the catching of the members 53 upon the upright standards 22 and 23 of the base structure. When a sufficient amount of material has been placed in the baling press, it is then 85 returned to the position shown in Fig. 1 by a reversal of the operation above described and the packing plunger is forced downwardly into the press receptacle, it being 90 understood that the fingers 38 are in position to maintain the end pieces rigidly against outward movement and that the latches 40 are in position to lock the side pieces against outward movement, and further, the receptacle is now resting upon the 95 supporting channels 19 and not upon the rollers 48. When the pressing action is completed, however, it sometimes becomes a difficult matter to extract the bale from the baling press receptacle and I overcome this 100 difficulty by the provision of the eccentric elements under the control of the levers 39. By simply swinging the levers 39 downwardly and outwardly, the pins 38 are 105 moved from operative position and the end pieces formed to yield sufficient to leave the bale comparatively loose within the receptacle. Then, or before this, one of the side pieces may be removed by releasing the latch elements 40 and simply lifting such 110 side piece outwardly.

From what I have described, it will be apparent that I have devised a baling press having a base structure and a baling receptacle which is mounted in a position to have 115 its bottom rigidly supported upon angle irons and yet which may be readily moved into a position best suited for filling. This alteration of position for filling, is not absolutely essential, but it is desirable, as for instance, where it may result in a saving of time to move the receptacle into position beneath a chute. The roller levers are readily manipulated to lift the receptacle into such a position as will permit it to freely roll to the inclined position described and such roller levers are further operative as described to limit the said rolling movement. The structure is also such that there is no difficulty in withdrawing a bale from the 120 125 130

receptacle when so desired, for the reason that the side pieces may be unlocked and permitted to yield.

One other important feature of my invention resides in the peculiar form of channel for supporting the bases of the side pieces, which peculiar channel has a distinct function. By reference to the drawings, it will be seen that the structure alluded to, comprises the cut-out ends of the bars upon the base of the receptacle and their coactive series of studs. The cutting out of these ends, does not decrease the rigidity of support of the side pieces and yet the cloth which may be utilized to wrap the bale is given sufficient freedom to avoid stretching and tearing of the same. Actual workers in the art will appreciate this advantage.

What I claim, is:

20 1. A baling press comprising a framework, a receptacle, a plunger for reciprocation in said receptacle, a plurality of racks carried by said plunger, a shaft carried by said framework, a plurality of gears upon 25 said shaft for coaction with said racks, a gear wheel, an internally and externally toothed idler carried by said shaft, a pinion sildably keyed to said shaft and constructed to mesh with said internal gearing, hand 30 operable means for reciprocating said plunger when said pinion is out of mesh, and supplemental hand operable means for reciprocating said plunger when said pinion 35 is in mesh, said last means increasing the effectiveness of said plunger under the same condition of applied manual force.

2. A baling press comprising a base, a plunger, a receptacle, operating levers pivotally carried by said receptacle, and rollers 40 rotatably mounted on one end of said levers and adapted to bear on said base.

3. A baling press comprising a base, a trackway forming a portion of said base, a plunger, a receptacle, operating levers pivotally carried by said receptacle opposite 45 each other on opposite ends, a connecting piece between said levers, and rollers rotatably mounted on said levers and adapted to bear on said trackway.

tably mounted on said levers and adapted to bear on said trackway.

4. A baling press comprising a base, a 50 plunger, a receptacle, operating levers pivoted intermediate their ends, and rollers carried by one end of said levers and adapted to facilitate movement of said receptacle on said base when the opposite ends of said 55 levers are moved.

5. A baling press comprising a base, a trackway forming a portion of said base, a 60 plunger, a receptacle, a U-shaped operating lever whose legs are pivoted to said receptacle intermediate their ends, and rollers carried by the free ends of said legs adapted to permit movement of said receptacle by upward movement of the joining piece of 65 said U-shaped lever.

6. A baling press comprising a base, a double inclined trackway forming a portion of said base, a plunger, a receptacle, U-shaped operating levers on both sides of said 70 receptacle whose legs are pivoted to the ends thereof intermediate their ends, rollers carried by the free ends of said legs adapted to permit movement of said receptacle by upward movement of the joining piece of 75 one of said U-shaped levers, and stops adapted to coöperate with said levers and constructed to permit movement of said receptacle up 80 said trackway when the opposite lever is elevated but prevent rearward movement under the same conditions.

7. A baling press comprising a receptacle, a series of base boards in said receptacle, a series of alining studs adjacent said base boards, the ends of said base boards and said 85 studs forming a socket, a side of said receptacle fitting removably within said socket, said studs being rounded and said base board ends being cut out.

In testimony whereof I affix my signature in presence of two witnesses.

JOHN YOUNG.
